UNITED STATES PATENT OFFICE.

LOUIS WELKER, OF WILLIAMSPORT, PENNSYLVANIA.

DESIGN FOR A TABLE-LEG.

SPECIFICATION forming part of Design No. 22,997, dated January 2, 1894.

Application filed November 29, 1893. Serial No. 492,393. Term of patent 14 years.

To all whom it may concern:

Be it known that I, LOUIS WELKER, a citizen of the United States, residing at Williamsport, in the county of Lycoming and State of Pennsylvania, have invented a certain new and useful Design for Table-Legs; and I do hereby declare the following to be a full, clear, and exact description of the invention, which will enable others skilled in the art to which it pertains to make and use the same.

My invention relates to designs for table legs, which are particularly adapted for knock-down tables, and is used in connection with many different forms of knock-down tables.

In the accompanying drawings—Figure 1 is a side elevation of a table leg embodying my new design, and Fig. 2 is a plan view hereof.

In all of the above views corresponding parts are designated by the same letters of reference.

The leading features in my design consist of a table leg with an upper end of a generally square shape with one of its corners bevelled off, and with a projection protruding 25 from the bevelled corner.

A, is the upper end of the table leg, of sufficient depth to accommodate the ordinary side pieces of the table, said upper end being of the general square shape shown. The inner 30 corner of the upper end is bevelled away as shown, to form a flat surface a. The two adjacent sides b, and c, are at right angles to each other. The outer sides d and e are plain and corner f, is ornamented as shown. 35

Extending out from the surface A, is a projection g, which constitutes a necessary part of my new design.

B, is the lower part of the leg.

What I claim is—

The design for a table leg, herein shown and described.

In testimony whereof I affix my signature in presence of two witnesses.

LOUIS WELKER.
